UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed January 24, 1922. Serial No. 531,353. Renewed January 10, 1925.

To all whom it may concern:

Be it known that I, BURNHAM C. STICKNEY, a citizen of the United States, residing in Elizabeth, in the county of Union and State of New Jersey, have invented certain new and useful Improvements in Type-writing Machines, of which the following is a specification.

The present invention relates to sound-deadening casings for typewriting machines, and more particularly to the window thereof through which the printing is visible to the operator.

In a casing of this character, the top is ordinarily arched upward from the rear to accommodate the carriage of the typewriting machine; and, to eliminate unnecessary bulk and weight, it is thence sloped downward and forward to the front of the casing. The window has usually been a flat window set in this forwardly-sloping part of the top of the casing. It has been found that lights, when in certain positions, above the typewriter desk or stand, are objectionably reflected into the eyes of the operator by such a window; and various expedients, such as having the window-pane angularly adjustable, within moderate limits, have heretofore been resorted to for diversion of such objectionable reflections.

It is an object of the present invention to substitute, for the flat sloping window-pane, a window comprised of a plurality of panes set at an angle to one another, and set at such angles that no properly positioned light will be objectionably reflected to the operator. In the preferred form of the invention, I provide a window with two such panes, one a horizontal pane, which will cause the rays from a light, over the stand or desk, to be reflected upward, above the operator's line of vision, and the other a vertical pane, which will cause any rays reflected therefrom to pass below the operator's line of vision. Either the vertical or the horizontal pane may be in the operator's line of vision of the platen, and the other pane will serve to assist in the illumination of the interior of the casing. Only the pane which is in the operator's line of vision of the platen need be transparent; the other pane may be translucent, and, if desired, may have a ground outer surface, so that there can be no objectionable re-

flection therefrom, regardless of the position 55 of the light.

A further object of the invention is the provision of means whereby the window thereof may be interchangeable with the ordinary flat sloping window, so that one 60 or the other may be used, according to lighting conditions or taste.

A further object of the invention is the provision of means whereby the window may be inverted, at will, in its frame; that 65 is to say, may be set so as to be either convex or concave with respect to the outside of the cover. In the convex setting of the window, the vertical pane will ordinarily be at the front of the casing, and will be 70 the pane through which the operator views the printing. In the concave setting of the window, on the other hand, it will ordinarily be the horizontal pane through which the operator views the printing; this pane extending into the casing and connecting with the vertical pane which depends into the casing at the rear of the window-frame.

A further object of the invention is the provision of means whereby the window 80 may be angularly adjusted to divert reflections of improperly positioned lights. In this connection, it will be understood that the invention is not restricted to a window, the panes of which are set vertically and horizontally, or at right angles to each other, or even to a window in which there are but two panes. In some forms of the invention, one of the panes need not be of light-transmitting material.

Other features and advantages will hereinafter appear.

In the accompanying drawings,

Figure 1 is a view in cross-sectional side elevation of a casing embodying the features 95 of the present invention; the platen and platen-carriage of a typewriting machine being indicated in dotted lines therein.

Figure 2 is a front view, taken on the line 2-2 of Figure 1.

Figure 3 is a view in cross-sectional side elevation through the upper part of the cover of the casing, showing a different form of window therein.

Figure 4 is a view in cross-sectional side elevation through the upper part of a casing-cover, embodying, as a window therefor, a modified form of the invention.

Figure 5 is a broken front view, in cross-section on the line 5—5 of Figure 4, of one end of the casing-cover.

Figure 6 is a view in cross-sectional side 5 elevation, showing the window of the Figure 1 style and means whereby the same may be angularly adjusted in the casing-cover which supports the same.

Figure 7 is a front view, in cross-section 10 on the line 7—7 of Figure 6, taken at one end of the cover to show the cover-adjusting means.

Referring to the drawings, the casing is 15 shown as comprising a body-portion 10 and a cover-portion 11 hinged at 12 to the body-portion. The casing is preferably provided with a sound-deadening lining (not shown). The position of the platen is indicated in dotted lines at 13, Figure 1, on a carriage 20 14, also indicated in dotted lines.

The top of the cover is provided with an opening 18 for a window of glass or other transparent material, through which the operator may observe the printing on the 25 platen 13. The casing-cover is preferably a casting having as part thereof an inwardly-depending rectangular rib 19, which serves as a frame for the window.

In the Figure 1 embodiment of the invention, the window comprises a horizontally-disposed pane of glass 20 and a vertically-disposed pane of glass 21, both supported on triangular metal plates 22, one plate 22 being at each side of the window-frame, as 30 shown in Figure 2. For supporting the plates 22, the ribs 19 at the ends of the window-frame are flanged, as at 23, to serve as seats for the faces of the flange 24 of the plates 22. Clips, in the form of flat metal 35 pieces 25, secured by screws 26 to the cover at the ends of the window-frame, overlie the flanges at the base of the plates 22 and serve to hold the plates to the cover. By loosening or removing the screws 26, the clips 25 may 40 be swung or lifted from the flanges 24 of the plates 22, so as to permit removal of the window from the frame. Packing, in the form of a strip of felt 27, is preferably inserted between the flanges 24 of the plates 22 and the flanges 23 on which the same are 45 seated. For attachment of the window-panes 20 and 21 to their supporting plates 22, the latter are provided, at their upper and forward edges, with flanges 28 and 29, respectively. The panes 20 and 21 are set 50 against the flanges 28 and 29, and are secured to their supporting flanges by screws 30. Packing-strips 31 and 32 are preferably inserted between the panes and the flanges, 55 to which they are attached, and the packing 31, as shown in Figure 1, extends across the top of the front pane 21, where the pane 20 overlies the same. For removal or placing 60 of the window, shown in Figure 1, the screws 30 need not be removed. The supporting 65

plates 22 and the panes 20 and 21, secured thereto, are removable or placeable as a unit. As shown in Figure 1, the front stretch of the window-frame formed by the bead or rib 19 is shaped to provide an inwardly-directed flange 33; and the lower front edge of the vertical pane 21 sets into a packing and sound-deadening strip 34, which serves as a facing for the flanged forward stretch of the window-frame. The rear stretch of the window-frame is likewise provided with a packing and sound-deadening strip 35, against which the rear edge of the horizontal window-pane 20 sets. The lower edge of the pane 21 and the rear edge of the pane 20 are preferably rounded as shown, more effectively to be seated in the packing-strips and close the joints at the edges of the window.

In the embodiment of the invention shown in Figure 1, the operator may observe the printing on the platen through the transparent vertical pane 21; and no light-rays striking down upon the pane 21 can be reflected to the operator's eyes. Except for the desirability of having the interior of the casing sufficiently illuminated, the pane 20 might be opaque. The pane 20 need not be transparent to provide light for the interior of the casing; it may be of ground glass or other translucent material. If the upper surface of the pane 20 be ground, no objectionable reflection will be thrown therefrom to the operator, regardless of the position of the light. With the lights in the preferable position, substantially over the typewriting machine, light-rays striking the pane 20, in its Figure 1 horizontal position, would, if the upper surface of the latter were smooth or polished, be reflected upward at such an angle as not to strike the operator's eyes. In ordinary cases, therefore, the pane 20 may be made of the usual transparent glass; but, as above noted, it may, where the positions of the lights render it desirable, be made of ground glass or translucent material.

Figure 3 shows a transparent pane of glass 40 set into the opening 18 in the cover 11 of the casing at the same slope as the cover. This Figure 3 angular setting of the pane is 115 not new with the present invention, but is here illustrated to show the interchangeability of the Figure 1 and Figure 3 forms of window when lighting conditions make one or the other form more desirable. As shown in Figure 3, the pane 40 may be set upon the flanges 23 (see Figure 2) of the window-frame with the lower front edge of the pane 40 on the front flange 33 of the window-frame, and with the rear edge of the pane 40 resting against the packing 35 on the rib 19, at the rear of the window-frame. The fastening devices 25—26 (see Figures 2 and 3), heretofore described, serve to hold the pane 40 in place, the metal strips 25 being shown 125

in Figure 3 as overlying the side of the pane 40 in the same manner as in Figure 2 they overlie the flanges at the bases 24 of the supporting plates 22.

- 5 Figures 4 and 5 show a modification of the invention in which, as in Figure 1, the window has a vertical pane and a horizontal pane. In Figure 4, however, the vertical pane 41 depends into the casing from the 10 rear of the window-frame, and the horizontal pane 42 projects into the casing from the front of the window-frame. The panes 41 and 42 are mounted upon, and supported by, plates 43 at the sides of the window-frame. 15 The attachment of the panes 41 and 42 to the plates 43 may be the same as the attachment of the panes 20 and 21 to the plates 22 in the Figure 1 form of the invention; that is to say, the plates 43 may, as shown in Figure 20 4, be provided with flanges 28, to which the panes are attached by screws 30. The plates 43 are also provided with flanges 24, see Figure 5, such as shown at 24 in Figure 2, whereby the window may be supported as a 25 unit from the flanges 23 at the sides of the window-frame. In the Figures 4 and 5 form of the invention, the joints are packed with sound-deadening material in the same manner as shown in Figure 1. The window 30 structure of the Figures 1 and 4 modifications, although not necessarily identical, is made preferably identical, so that there may be interchangeability between the Figures 1 and 4 embodiments of the invention. To 35 change from the Figure 1 to the Figure 4 form of the invention, or vice versa, it is merely necessary to remove the window, after loosening or removing the screws 26; swing the same over; again seat the flanges 40 24 and the flanges 23; and reset the fasteners 25—26. Obviously the arrangement of the different parts must be such as to give suitable clearance for the carriage 14 when the window is in its Figure 4 position. Such a 45 result may be obtained by suitable variation in the dimensions of the panes 41 and 42 and of the frame in which they are held or by arranging the casing and the machine so that the carriage will be in a sufficiently low 50 position in the casing.

Where the Figures 1 and 4 forms of the invention are to be interchangeable, however, the pane 20 should be transparent, because, in the Figure 4 form of the invention, it is 55 through the horizontal pane 42 that the operator observes the printing on the platen. In the Figure 4 form of the invention, the vertical pane may be opaque, but is preferably transparent or translucent, better to illuminate the interior of the casing. No ordinary placement of lights would enable rays to be reflected from the vertical pane 41 in Figure 4, to the eyes of the operator; and, with the lights arranged in the preferred 60 65 position over the machine, any rays reflected

from the horizontal pane 42 would be directed upward over the operator in such direction as not to strike his eyes. Whether or not the Figure 4 window structure is identical with the Figure 1 structure, so as to be 70 interchangeable therewith, it may be interchangeable with the Figure 3 window.

Figures 6 and 7 show substantially the Figure 1 window construction together with means whereby the window may be angularly adjusted. In Figure 6, the rear edge of the horizontal pane has a U-shaped binding 45, preferably of metal, secured thereto by screws or rivets, and having formed thereon, and extending longitudinally thereof, at the 80 rear of the pane a rounded bead 46, which is set into a correspondingly rounded recess 47 in the edge of the cover 11 which forms the rear of the window-frame. For holding the bead 46 in the recess 47, there are provided 85 guards 48, of which there are preferably two, one near each end of the window. The guards 48 are shown as flat metal pieces secured to the cover 11 by screws 49, and adapted, when the screws are loosened or 90 removed, to be swung or lifted, so that the bead 46 may be removed from its seat 47 when it is desired to remove the window bodily from the cover. The bead 46 and its 95 seat 47 being round, permit of easy angular adjustment of the window; and the guards 48 terminate short of the neck formed by the bead 46, so as not to interfere with such angular movement of the window.

In order that the window may have ample angular movement without opening joints in the casing, the forward reach of the window-frame is provided with a wide flange 50 curved on an arc struck from the pivot-point at 46, and preferably lined with a 100 strip 51 of sound-deadening material, such as felt, into which the lower edge of the vertical pane 21 may set in any angular position of the window. As shown in Figures 6 and 7, the side reaches of the window-frame also 105 have flanges 52, wide enough and of such shape as to prevent opening of joints at the sides of the window, and the flanges 52 are also provided with strips 53 of felt.

The pane-supporting plates 54, in Figures 6 and 7, have flanges 28 and 29, such as shown in Figure 1, for attachment thereto of the window-panes, but do not require the flanges 24 for supporting or securing the window in position. In the Figures 6 and 7 form of the invention, the window is supported and secured in position by means of ears 55 projecting outward from the plates 54. The ears 55 are perforated, as at 56, to receive reduced portions or necks 57 in 115 adjusting screws 58, which latter are threaded into the metal of the casing-cover 11 and into lugs 59 which are cast on the casing to provide more ample bearings for the screws 58. The screws 58 are provided with 120 125 130

knurled heads 60, by means of which the same may be turned. The shoulders formed by the reduced portions or necks 57 of the screws 58 engage the ears 55, to cause the window structure to be lifted or lowered as the screws are turned. The perforations 56 in the ears 55 are of such size as to allow for angular movement of the window structure.

10 In the structure of Figure 6, as in the structure of Figure 1, the operator will observe the printing on the platen through the vertical pane 21. In connection with Figure 1, it has been stated that, with the lights 15 in the preferred position, a transparent or polished pane 20 would reflect the rays upward in a direction in which they would not strike the operator's eyes. In the event the lights are not so positioned, but are where a 20 reflection from horizontal pane 20 would annoy the operator, the objectionable reflection may be eliminated by swinging the window angularly, in one or the other direction, by means of the adjusting screws 58 in 25 the manner described.

This application is in the nature of an improvement upon the devices shown in the application of John Waldheim, Serial No. 512,741, filed November 4, 1921, and 30 in my co-pending application, Serial No. 513,001, filed November 5, 1921, and upon the devices shown in the patent granted to said John Waldheim, July 1, 1924, No. 1, 499,709. Said Waldheim application and 35 patent are in the nature of improvements upon the machine covered by an application Serial No. 381,259, filed by me May 14, 1920; but the present case contains no claim that could be made in said application No. 40 381,259.

Variations may be resorted to within the scope of the invention, and portions of the improvements may be used without others.

Having thus described my invention, I 45 claim:

1. A sound-deadening casing, for a type-writing machine, having in the wall thereof a window comprising two portions of light-transmitting pane inclined at such an angle 50 as to concave outwardly and to divert from the operator any lights reflected therefrom; one of said pane portions being transparent and being in the line of the operator's vision of the printing position on the platen when 55 the machine is in the casing.

2. A sound-deadening casing, for a type-writing machine, having in the wall thereof a window comprising two angularly disposed portions of light-transmitting pane to 60 divert from the operator any lights reflected therefrom; one of said pane portions being transparent and extending rearwardly from the front edge of the window across the line of vision of the printing position on the 65 platen of a machine in the casing, and the

other pane portion extending upwardly from the rear edge of the first pane portion and being for illumination of the interior of the casing.

3. A sound-deadening casing for a type-writing machine having a window-frame in the top thereof, and window-panes seatable in different light-reflecting positions selectively in said window-frame and effecting different angles of reflection of light rays 70 from the window, to vary the angle of reflection of the light rays received from different directions and to direct them away from the line of vision of the operator.

4. A window for a sound-deadening casing comprising two panes inclined with reference to each other, and triangular members connected with the ends of said panes and having at their free edges outwardly-extending flanges substantially in a plane 75 passing through the free edges of said panes.

5. A sound-deadening casing for a type-writing machine, comprising a work-viewing window-frame with depressed seats at its side edges, and a window for preventing 80 objectionable reflection, comprising two transparent panes inclined to each other and having their front and rear edges so spaced as to extend across said window-frame from front to rear, and triangular ends provided 85 at their free edges with outwardly-extending flanges to rest in said seats and lying in a plane through the free edges of said panes, so that the latter will properly engage the front and rear edges of the window-frame 90 irrespective of the convex or concave position of said window.

6. A sound-deadening casing for a type-writing machine, high enough at the rear to give substantial clearance above the type-writer-carriage, and comprising a downwardly and forwardly inclined top, a window having two panes perpendicular to each other, and a window-frame in said inclined top having a vertical wall at its rear edge and at its forward edge a vertical wall and a horizontal ledge extending rearwardly therefrom, so that, when said window is placed in said frame in one position, the outside surface of one of said panes will lie against the vertical wall at the forward edge of the window-frame, and its edge will rest on said ledge, and the edge of the other pane will rest against the vertical wall at the rear of the window-frame; and, when placed in another position, the outer face of one of said panes will rest upon the ledge at the front edge of said window-frame, and its edge will rest against the adjacent vertical wall, and the outer face of the other pane will rest against the vertical wall at the rear edge of said window-frame.

7. A sound-deadening casing for a type-writing machine, high enough at the rear to give substantial clearance above the type- 120

- writer-carriage, and comprising a downwardly and forwardly inclined top, a window having two panes perpendicular to each other, a window-frame in said inclined top 5 having a vertical wall at its rear edge and at its forward edge a vertical wall and a horizontal ledge extending rearwardly therefrom, so that, when said window is placed in said frame in one position, the outside 10 surface of one of said panes will lie against the vertical wall at the forward edge of the window-frame, and its edge will rest on said ledge, and the edge of the other pane will rest against the vertical wall at the rear of 15 the window-frame; and, when placed in another position, the outer face of one of said panes will rest upon the ledge at the front edge of said window-frame, and its edge will rest against the adjacent vertical wall, 20 and the outer face of the other pane will rest against the vertical wall at the rear edge of said window-frame; and packing-strips at the forward and rearward edges of said window-frame, the free edges of said panes 25 being rounded for effective seating in said packing-strips.
8. A sound-deadening casing for a type-writing machine having in the wall thereof a window consisting of two panes connected 30 together and forming a unit adjustable with respect to said wall and varying the direction of reflection of light rays for directing the same away from the line of vision of the operator.
- 35 9. A sound-deadening casing for a type-writing machine, high enough at the rear to give substantial clearance above the typewriter-carriage, and comprising a downwardly and forwardly inclined top, a rectangular frame in said inclined top, and a work-viewing window comprising two panes, angularly disposed and connected together as a unit, and being adjustable in said frame, to avoid objectionable reflection of 40 light to the operator.
- 45 10. A sound-deadening casing for a type-writing machine having in the wall thereof a window-casing and a window-sash having therein a window having portions angularly disposed with relation to each other, said window being adjustable by overturning said angularly-disposed portions in said window-casing, changing the direction of light rays reflected from said window, and directing 50 the same away from an operator's line of vision.
- 55 11. A sound-deadening casing, for a type-writing machine, having a forwardly and downwardly sloping top with a rectangular window-opening therein, and a window to fit 60 said opening and comprising two portions of light-transmitting pane inclined at an angle to each other to extend out of the plane of said opening, one of said pane portions being transparent and being in the line of the operator's vision of the printing position on the platen when the machine is in the casing; and means to close the triangular openings formed at the sides of 65 said pane portions. 70
12. A sound-deadening casing, for a type-writing machine, having a window-opening therein, a window for said opening comprising two portions of light-transmitting pane offset at an angle from one another; one of 75 said pane portions being transparent and being in the line of the operator's vision of the printing position on the platen when the machine is in the casing, and means for supporting said window in its frame in either 80 its convex or concave position with respect to the top of the casing. 80
13. A sound-deadening casing, for a type-writing machine, having in the wall thereof a window comprising two portions of light-transmitting pane set at right angles to each other; one of said pane portions being transparent and protruding horizontally into the casing across the line of the operator's vision of the printing on the platen when the machine is in the casing, and the other of said 90 pane portions projecting vertically from the rear edge of the horizontal pane portion to the top of the casing for illumination of the interior thereof. 95
14. A sound-deadening casing for a type-writing machine, comprising a window-frame in the wall thereof and a window having portions angularly disposed with relation to each other, adjustable by overturning said portions in said frame, so that for one position said portions are in convex 100 relation with respect to the casing, and for another position are in concave relation with respect to the casing, whereby the direction of reflected light rays are varied with respect to the line of vision of an operator. 105
15. A sound-deadening casing for a type-writing machine, having in the top wall thereof a window-frame having portions thereof angularly disposed, said window-frame being adjustable by overturning the same in said wall. 110

BURNHAM C. STICKNEY.
